2,227,655

CEILING OR WALL RECESSED LIGHTING
Fixture ConstructionJoseph Levy, New York, N. Y., assignor to Century
Lighting, Inc., a corporation of New York

Application March 2, 1940, Serial No. 321,818

2 Claims. (Cl. 240—78)

This invention relates to electric lighting fixtures or unit constructions and more particularly is directed to an improved electric lighting fixture of the recessed ceiling or wall type provided with a swingable door through which normally the light beams are projected from a light source enclosed in the fixture, said door being made conveniently movable to permit free access into the interior of the fixture for replacing the incandescent lamp, for repairs or for cleaning yet limiting the movement of the door against coming into accidental contact with the ceiling or wall regions surrounding the door, and thereby eliminate marring of the surface thereof.

Among the objects of the invention is to generally improve electric lighting fixture constructions of the character described, which shall comprise few and simple parts that are readily assembled and adapted to form recess ceiling or wall type fixtures of neat and attractive appearance, which shall have swingable doors fitted with transparent panels to permit convenient replacement of interior parts yet eliminating all possibility of marring the ceiling or wall surfaces surrounding the door, which shall be inexpensive to manufacture, and practical and efficient to a high degree in use.

Other objects of this invention will in part be obvious and in part hereinafter pointed out.

The invention accordingly consists in the features of construction, combinations of elements and arrangement of parts which will be exemplified in the constructions hereinafter described and of which the scope of application will be indicated in the following claims.

In the accompanying drawings, in which is shown various possible illustrative embodiments of this invention,

Fig. 1 is a side elevational view of a recessed ceiling type of an electric lighting fixture installation embodying the invention, partly broken away to expose the interior construction.

Fig. 2 is a cross-sectional view corresponding to a cut taken on line 2—2 in Fig. 1.

Fig. 3 is a fragmentary side elevational view similar to Fig. 1, showing the swingable door or cover in full open position whereas Fig. 1 shows the same securely closed.

Fig. 4 is an enlarged fragmentary cross-sectional view taken on lines 4—4 in Fig. 1.

Fig. 5 is a cross-sectional view similar to Fig. 2 of a modified construction of the invention.

Referring in detail to the drawings, 10 denotes an electric lighting fixture constructed to embody the invention, and as here shown is installed in a

ceiling C building structure as an overhead source of illumination. Said fixture 10 may also be utilized to serve as side illuminating means by installing it in a vertical wall structure (not shown) in the same manner as herein described for the 5 ceiling installation.

The fixture 10 may be connected to a building wiring system of any conventional construction through a junction or outlet box 11 located behind the ceiling C. Conductor wires (not shown) 10 which carry electrical power from a suitable source into the box 11 in the well understood manner connects with a socket receptacle 12 of standard construction, the latter being fastened by screws 13 to a cover plate 14 of said box 11. 15 Said plate 14 has a center opening for giving access to the receptacle 12 through which the base of an incandescent lamp B mounted in the receptacle 12 extends as shown in Fig. 1.

Where it is desirable to use standard parts 20 readily obtainable in the market in the construction of fixture 10, there is provided a suitable reflector 16 for the bulb B which may be secured against the cover plate 14 by said screws 13 and a separate sheet metal housing 17 for enclosing 25 the side and rear of fixture 10 as shown in Fig. 1. The housing 17 is supported on a door frame 18 which may be neatly fitted in an opening cut in the ceiling C. Said frame 18 preferably may be cast or molded and has a continuous outwardly 30 extending flange 18a which rests on the rear side of the ceiling C and is secured thereto in any suitable manner as by screws 19. The frame 18 also may have a continuous flange 18b extended at right angles to flange 18a, which preferably 35 should be made of a width equal to the thickness of the ceiling C to provide a finishing sheathing for the cut surface of the ceiling opening against which said flange 18b abuts. Aligning with the inner surface 18c of the flange 18b and extending in relatively opposite directions projecting lugs 18d are provided for fastening the frame 18 to the housing 17.

As seen from Fig. 1, the frame 18, housing 17 and the junction box 11 form a complete enclosure 45 for the bulb B, receptacle 12 and reflector 16 with the exception of the open side of the fixture 10 which is provided with a swingable door 20, the latter being hinged to the housing 17 to cooperate with the frame 18 by means of spaced 50 pairs of links 21, 22. The door 20 may be made of cast or molded material having T-section structure, the inner and backwardly extended portions 20a and 20b, respectively, thereof forming a seat in which a glass or lens 21c is secured. 55

The outwardly extending portion 20c of said door structure serves as a continuous trim for covering the joint between the frame 18 and door 20.

Each set of links 21 and 22 has one end of each 5 21a and 22a, respectively, pivoted on spaced pins 23 and 24, respectively, the latter being fitted to extend from spaced points along frame portion 20b, as shown in Figs. 1 and 2. Cotter pins 27 and 28 retain the link ends 21a and 22a, respectively, on pins 23 and 24, respectively. The other ends 21b and 22b of links 21 and 22, respectively, are pivoted on spaced pins 25 and 26, respectively, said pins being fitted to extend from an angle piece 29 which is secured to the side wall 17a of the housing 17. As seen in Figs. 1 to 4, spacing collars 25a and 26a are provided on pins 25 and 26, respectively, for aligning the link ends 21a with 15 21b, and 22a with 22b. As shown in Figs. 1 and 4, a single lock pin 30 may be used to retain 20 the link ends 21b and 22b on pins 25 and 26, respectively.

Each link 21, the longest of the set, is a flat bar which preferably extends about three quarters the distance from the side housing wall 17a 25 supporting the link end 21a to the opposite housing side wall 17b. Each link 22, shorter than link 21, instead of being of uniform cross-section like the latter has an extended portion 22c which serves as a stop when effective to positively retain 30 the door 20 in a fixed open position and cooperates with link 21 to limit such open swinging so that the door cannot come into contact with the ceiling surface surrounding the frame 18 except when closed as shown in Figs. 1 and 4.

35 In practising the invention the fixture 10 is constructed as described above and the parts assembled as shown in Figs. 1, 2 and 4. The housing 17 is provided with a central opening in the wall 17c thereof slightly smaller than the open 40 side of the junction box 12 and is fitted under the cover plate 14, being retained to the box 12 by suitable screws 31 as shown in Fig. 1. In assembling the housing 17 to the frame 18 it has been found that rim edges of the housing adjacent 45 the plane of the surface of the ceiling against which the door 20 abuts should be located just above said plane as shown in Figs. 1, 3 and 4. The housing side 17b can be provided with an inturned flange 17d along said rim edge, 50 said flange 17d being drilled and threaded at 32 to receive the pointed end screw 33 which has its head seated in the door portion 20c. Another pointed end screw 34 is provided in the door portion 20c oppositely disposed to screw 33, the 55 screw 34 engaging in a drilled and threaded hole 35a in angle piece 35 extending from the inside surface of housing side 17a inwardly from the rim edge of the housing 17 as shown in Figs. 1 and 3. In order to properly locate the rim edge 60 of housing as described above, space slot and screw fastening means 36 are provided, the screws 36a being inserted to extend through the housing slots 36b and engaging in the threaded holes 36c in frame portion 18c as shown in Figs. 1 and 3. By loosening the fastening means 36 the housing 17 can be adjusted by raising or lowering to proper position, and said fastening means then tighten to rigidly retain same. With 70 all the parts assembled and the screws 33 and 34 in place, the fixture door is tightly closed, a rubber or felt gasket 37 being provided if desired along the inner side of the door flange 20c to cushion the door closure, and fibre washers 38 75 may be provided on the necks of the screws 33

and 34 to prevent said screws from accidentally dropping out of place.

To open the fixture 10 for replacing the lamp B, or for any other purpose, the screws 33 and 34 are loosened until they disengage the threaded 5 holes 32 and 35a, respectively, the door 20 can then be readily swung to open from the position shown in Fig. 1 to that shown in Fig. 3. In the latter position the door 20 is prevented from further swinging and cannot be made to touch 10 or mar the ceiling surrounding the frame 18. This is accomplished by the extended link portion 22c acting as a stop against angle piece 29 at the rim portion of the housing side 17a, the link 21 then firmly bracing the suspended door 15 structure in said open position, as seen from Fig. 3.

The door 20, although shown here as being square, may have other rectangular shapes or 20 may be oval or the like.

Where the door 20 is relatively small, the modified form shown in Fig. 5 may be used. Here only one side of the door may be provided with a set of two links 21 and 22 and on the opposite side the long link 21 may be omitted. The short 25 link 22 alone on the latter side will be found sufficient for all practical purposes.

It should be noted that in both forms of the invention shown and described that the links 21 and 22 of each set cooperate in the swinging 30 movement of the door 20 to positively control same so that no part of said door 20 can come in contact with any surface surrounding the door 20 except in the closed position thereof.

It will thus be seen that the lighting fixture 35 and unit construction as provided achieve the objects of the invention and are well adapted to meet the conditions of practical use in an efficient manner.

As various embodiments might be made in the 40 above invention and as various changes might be made in the embodiments above set forth, it is to be understood that all matters herein set forth or shown in the accompanying drawings are to be interpreted as illustrative and not in a limiting 45 sense.

Having thus described my invention, I claim as new and desire to secure by Letters Patent:

1. A lighting fixture casing comprising a housing 50 for a light source formed with an open side, a door frame fitted to said open side, a door carrying a light transmitting member through which light rays are projected from said source and forming a closure over said door frame, sets of two unequal link bars having one end of each bar 55 pivoted to a side of said frame, the pivoted ends of the longer bars being located inwardly of said open side a spaced distance from the pivoted ends of the shorter bars, the other end of each bar being pivoted to the door, the pivoted ends of 60 longer bars on the door being located at a greater distance from said frame side than the pivoted ends of the shorter bars, at least one of the shorter bars having an extended portion serving as a stop to abut with said frame side for limiting 65 the swinging movement of the door away from the frame.

2. A lighting fixture construction of the recessed ceiling or wall type comprising a casing having an open side for housing a light source, 70 a door frame fitting into an opening in said ceiling or wall in which the fixture is recessed, means adjustably securing the door frame to the casing within said open side, a door carrying a transparent member through which light rays from 75

said source project forming a closure over the door frame and extend beyond the latter to provide a trim covering the joint between said frame and door, means for swingably supporting the door to and away from said frame including at least one pair of cooperating bar links of unequal length, one end of each link pivoted to a side of the frame, the pivoted end of the longer link being located inwardly of said open side a spaced distance from the pivoted end of the shorter link, the other ends of the links being pivoted to the door, the pivoted end of the longer link on the door being located at a greater distance from

said frame side than the pivoted end of the shorter link, the shorter link having an extended portion serving as a stop means adapted to abut said frame side for limiting the swing movement of the door away from the frame and for positively preventing the door in open position to contact the ceiling or wall surface regions about the frame, and releasable fastening means extending through spaced portions of the door for retaining the latter in closed position to the 10 casing. 5

JOSEPH LEVY.
